UNITED STATES PATENT OFFICE.

EDWIN F. STEWART, OF WOODCLIFF, AND RAY POTTER PERRY, OF MONTCLAIR, NEW JERSEY, ASSIGNEES TO BARRETT MANUFACTURING COMPANY, OF NEW YORK, N. Y., A CORPORATION OF WEST VIRGINIA.

METHOD OF BURNING FUEL.

1,134,421.

Specification of Letters Patent. Patented Apr. 6, 1915.

Application filed March 17, 1914. Serial No. 825,348.

To all whom it may concern:

Be it known that we, EDWIN F. STEWART and RAY POTTER PERRY, citizens of the United States, and residents of Woodcliff, New Jersey, and Montclair, New Jersey, respectively, have invented certain new and useful Improvements in Methods of Burning Fuel, of which the following is a specification.

10 This invention relates to new and useful improvements in the commercial utilization of various combustible materials in a finely powdered or minutely subdivided state, such as coal tar pitch, asphalt, mineral pitch, resinous by-products, mineral oil residues, or other fuel materials, which have the characteristic of becoming soft and adherent when heated to comparatively low temperatures and therefore cannot be handled successfully 15 by existing devices which handle pulverized coal as a fuel.

Wherever we use the term "comparatively low temperatures" in this patent application we refer and limit ourselves to temperatures of from say 70° F. to 400° F., the temperatures within such range being low in comparison with that of the heat radiating from a furnace burning pulverized fuel.

In burning pulverized coal, it is customary to reduce it to a suitable fineness and blow it, mixed with air, as a carrier and for combustion, by means of a fan or blower through a plain metal nozzle into the furnace where it is burned. Ordinarily the metal nozzle becomes heated by radiation from the furnace, but does not attain such temperature as will soften and make adherent any particles of the pulverized coal which may impinge upon the inner surface 30 of the nozzle. If, however, an attempt is made to deliver pulverized coal tar pitch or resinous fuels through such a plain and heated nozzle, it is found that such minute particles of this material as are impinged upon the interior surface of the nozzle are so softened as to become adherent thereto, and gradually accumulate in a coke-like mass in the bore thereof. As a result the continuous delivery of the pulverized fuel to the furnace is interfered with seriously, and the nozzle may be completely choked by the accumulated coke. This is explainable by the

fact that pitches which may be hard enough to grind and pulverize at normal atmospheric temperatures are still softened and become adherent at temperatures of, say as low as 400° F., which would be insufficient to soften coal and make it adherent under the conditions of use.

Our invention consists in the application of a cooling medium to the delivery nozzle and in addition thereto other features of our apparatus as hereinafter described which are necessary to the object of preventing radiation of heat from the furnace to the nozzle wall, whereby the temperature of the entire nozzle is maintained below that at which the pitches and other similar fuels become soft and adherent.

By means of our invention a new and important field is opened up for the use of pitches, asphaltic and bituminous material, as pulverized fuels, which have a great inherent advantage over pulverized coal due to the fact that pitch, as an example, contains less than one quarter of one per cent. of ash, whereas pulverized coal contains ordinarily upward of ten per cent. It is thus evident that our invention is of especial importance for use in various metallurgical processes where the presence of ash from burned pulverized coal is a serious disadvantage, making it necessary either to provide special means for removing and handling the ash which is usually detrimental to material and process, or else to use oil or gaseous fuel as an alternative, either of which may relatively increase manufacturing costs, as compared with the new fuels herein described.

Wherever we use the terms "artificial" or "artificially" in this patent application we refer and limit ourselves to the use of these words as expressing that the device or arrangement is made or contrived by art or produced or modified by human skill and labor in opposition to such occurring naturally.

We are describing herein three special types of constructions of apparatus adapted to accomplish the primary object of our invention, which consists primarily in the positive or artificial cooling of a nozzle for delivering these pulverized fuels to a fur-

nace, but we do not confine ourselves to these three types, and may employ any other suitable and locally accessible means to secure the essential feature of artificially cooling the said fuel delivery nozzle and also artificially cooling other portions of the accessory apparatus which may assist in preventing the radiation of heat from the furnace to said fuel nozzle, all for the object and purpose as hereinbefore described.

The invention consists further in various details of construction, and in combination and arrangement of parts, which will be hereinafter fully described, and then specifically defined in the appended claims.

Our invention is illustrated in the accompanying drawings, which with the letters of reference marked thereon, form a part of this application, and in which drawings similar letters of reference indicate like parts in the views; in which—

Figure 1 is a central vertical section through our apparatus, as applied to a boiler furnace, parts being shown in elevation; Fig. 2 is a vertical longitudinal section of the apparatus itself, showing one form of nozzle construction with an orifice or baffle plate, whereby our primary invention of artificially cooling the nozzle walls by means of a circulating fluid is accomplished; Fig. 3 is a rear elevation of this form of nozzle construction, the furnace wall not being shown; Fig. 4 is an elevation and partial section of the orifice or baffle plate showing circulating pipes for the cooling fluid; Fig. 5 is a sectional detail of a combined form of the nozzle and orifice plate; Fig. 6 is a sectional detail of the furnace wall with our nozzle and orifice plate shown as a modified form of construction, wherein our primary invention of artificially cooling a pulverized fuel nozzle is accomplished by the combined effect of cool air and liquids, in which the air so used is discharged outside the furnace; Fig. 7 is an end elevation of Fig. 6 certain parts being broken away; Fig. 8 is a modified form of the general construction shown in Fig. 6 in which the air for cooling the nozzle is discharged into the furnace through the orifice plate; Fig. 9 is an end elevation of the nozzle and orifice plate construction shown in Fig. 8; Fig. 10 is a modified construction of the nozzle shown in Fig. 2 wherein the cooling liquid is circulated around the nozzle from a spray or shower pipe above; and Fig. 11 is an end elevation of the nozzle and orifice plate construction shown in Fig. 10.

We now describe three preferred forms of apparatus whereby the object of our invention as embodied in the artificial cooling of a pulverized fuel nozzle may be successfully accomplished or wherein this cooling may be applied to other necessary parts, as a further means of protecting the nozzle

from the radiating heat of the furnace, and all for the object and purpose hereinbefore described.

Reference now being had to the details of the drawing by letter, A designates a pulverized fuel nozzle as being connected to the outlet of the fan O, to which the said adherent fuel may be automatically fed by the device N, from the bin M, being finally discharged into the furnace B through an opening in the front wall, as at the orifice G, together with a predetermined volume of air admitted through the register P as a carrier and necessary agent for its combustion. To maintain continuous feeding of these adherent fuels into the furnace, we have discovered that the heat of the interior surface of the nozzle wall must not exceed average normal air and water temperatures by more than about 330° F., depending on the adherent temperature of the particular fuel employed, and this is accomplished by artificially cooling the wall of the nozzle with any fluid that may be circulated within an annular outer casing or jacket, shown as C, such as air, water, brine, oils, or a fluid that will absorb and carry away the heat radiated from the furnace sufficiently to maintain the temperature of the nozzle wall below the adherent temperature of the fuel. As a further means of preventing heat radiation to the nozzle A, we may provide as a part of this special apparatus, a chambered box or plate, as L, having a central orifice, as at G, to be mounted when required in the front wall of the furnace with its orifice registering with the opening of the nozzle, and cooled by the circulation of any designated fluid that may be supplied to the chamber from a suitable source by the inlet pipe, as H, preferably at the top of the plate, and discharged at the opposite side of the partition J, through the pipe I, thus giving complete circulation around the orifice and within the chamber of the plate.

The annular jacket of the nozzle is also supplied with cooling liquid, air or vapor from a suitable source, as by the pipe D, where a liquid is used, this pipe extending within the jacket of the nozzle, preferably at the top, and parallel to its axis, to a point near the furnace end of the chamber, where the liquid is discharged into the chamber and circulates back and around the nozzle to the outlet pipe E; or in case it becomes desirable to use air or vapor for cooling, this medium is supplied from a fan, as S, entering the jacket tangentially as shown by R, at the point T, circulating around the nozzle within the jacket and finally discharging from the opening V, at the extreme end of the nozzle.

It may be of advantage with some of the fuels hereinbefore described, and where a liquid is used for artificial cooling, to com-

bine the jacketed nozzle and chambered orifice plate as one piece of apparatus, shown in Fig. 5, wherein the walls of the nozzle and plate are so attached that one common cooling chamber will produce the desired effect, in which case circulation is maintained by means of the supply pipe H and the discharge pipe E, the pipes D and J being omitted. In other cases owing to peculiar characteristics of some of these fuels, it will be found to be desirable where air or vapor is used as a cooling agent, to conduct it from the nozzle jacket into the furnace through the orifice plate and there-
to mix it with the additional air and fuel entering through the nozzle. A form of construction to permit this effect is shown in Fig. 8, wherein the end wall of the jacket at the fire end is removed allowing the cooling air to enter the furnace, and which eliminates the discharge outlet V.

A modified construction and method for obtaining the necessary circulation of cooling liquid around the nozzle wall is shown in Fig. 10 and Fig. 11, in which case the jacket is eliminated and the supply and distribution of the cooling liquid maintained by the perforated pipe D¹ extending along the top of the nozzle parallel to its axis, and connected to a suitable source of supply from which the cooling liquid is sprayed, or allowed to flow over the outer surface of the exposed section of the nozzle, the extreme end being provided with a stop flange so that the water is collected and disposed of by the pan Z and the conductor pipe E¹, thus in some specific cases giving the same cooling effect as the jacket hereinbefore described.

While we have shown a number of modifications in the form and details of construction for our apparatus, it will be understood that this variation in form and manner of application is to a certain extent made necessary as a means of successfully utilizing all of the fuels hereinbefore described, by reason of their relatively varying and specific character, and that all the modifications of our apparatus herein described are intended to coöperate as an essential means for the application of our new and useful invention, which consists of artificially cooling the nozzle of the type, for example, commonly used for delivering pulverized coal to a furnace, thus making it possible to utilize the specific fuels hereinbefore mentioned, which have the quality of becoming adherent at comparatively low temperatures.

Having thus described our invention, what we claim and desire to secure by Letters Patent is:—

1. In the consuming of pulverized fuel which softens so as to become adherent at a temperature below 400° F., the method

which consists in cooling the surfaces with which such fuel makes contact in passing into the zone of combustion, so as to maintain their temperature below that at which such fuel becomes adherent.

2. In the burning of pulverized fuel which softens so as to become adherent at a lower temperature than 400° F., the method which consists in delivering said fuel in a stream into the place of combustion, and in circulating a cooling fluid around and adjacent said stream so as to maintain the temperature of the particles of fuel below that at which they would become adherent.

3. In feeding to a furnace a pulverized fuel which softens at a critical temperature below 400° F., so as to become adherent, the method which consists in delivering said fuel with a commingled current of combustion-supporting gas, and meanwhile maintaining the particles of fuel in said current below said critical temperature.

4. In feeding to a furnace a pulverized fuel which softens so as to become adherent at a critical temperature below 400° F., the method which consists in delivering said fuel in a stream with combustion-supporting gas, confining said stream against lateral expansion, and maintaining the temperature of the confining means below such critical degree.

5. In the operation of feeding into the combustion chamber of a furnace a pulverized fuel which softens so as to become adherent at a critical temperature less than 400° F., the method which consists in delivering said fuel in a blast through a conduit which is subjected to a much higher temperature than said critical degree, and at the same time maintaining the temperature of the surfaces of said conduit with which such stream of fuel makes contact below said critical temperature.

6. In feeding to a furnace pulverized fuel which softens so as to become adherent at a critical temperature less than 400° F., the method which consists in carrying said fuel through a chamber which is exposed to a zone of heat greatly in excess of said critical temperature, and in maintaining the surfaces with which said fuel makes contact at all times below said critical temperature.

7. The method of burning solid fuel which softens so as to become adherent at a temperature below 400° F., which consists in first pulverizing the same, then delivering it with a blast of combustion supporting gas through a restricted space to the point of combustion, and meanwhile maintaining the temperature in said space below that at which such fuel softens so as to become adherent.

8. The method of burning a solid fuel which softens so as to become adherent at a temperature below 400° F., which consists

- in first pulverizing said fuel, then conveying the same with a blast of combustion-supporting gas through a chamber to the point of combustion, and meanwhile maintaining the temperature within said chamber below that at which said fuel softens so as to become adherent.
9. The method of consuming a solid fuel which softens at a critical temperature below 400° F., so as to become adherent, which consists in first finely pulverizing said fuel, then delivering the same in a current of com-

bustion supporting gas to the point of combustion, and meanwhile maintaining the particles of fuel in said current below said critical temperature.

Signed at New York city in the county of New York and State of New York this 14th day of March 1914.
